UNITED STATES PATENT OFFICE.

GEORGE H. DIPPO, OF CHAGRIN FALLS, AND WILLIAM M. POWELL, OF CLEVELAND, OHIO, ASSIGNORS TO THE FERROSTEEL COMPANY, OF CLEVELAND, OHIO.

DESIGN FOR A HOT-AIR REGISTER.

SPECIFICATION forming part of Design No. 32,135, dated January 23, 1900.

Application filed December 26, 1899. Serial No. 741,683. Term of patent 14 years.

To all whom it may concern:

Be it known that we, GEORGE H. DIPPO, residing at Chagrin Falls, and WILLIAM M. POWELL, residing at Cleveland, in the county of Cuyahoga, State of Ohio, citizens of the United States, have invented and produced a new and original Design for Hot-Air Registers, of which the following is a specification, reference being had to the accompanying drawings, forming a part thereof, and in which—

Figure I represents a plan view, and Fig. II a cross-section, of our design.

As set forth in the drawings, the leading feature of our design consists of a series of webs *a* and *a'*, disposed at right angles to each other and of trapezoidal cross-section, as shown in Fig. II. At each crossing-point the webs diverge at opposite angles of forty-five degrees, forming two branches, and converge and

rejoin, forming thereby octagonally-formed spaces *b* and small square spaces *c*. The webs are disposed in a manner such that the shorter of the two parallel sides of the trapezoid of the cross-section shall be disposed at the upper side of the register, thereby giving the structure the appearance of a much lighter construction for a given area of the openings than if such disposition were not utilized. 25

What we claim is—

The design for a hot-air register substantially as shown and described.

Signed by us this 21st day of December, 1899.

GEO. H. DIPPO.
WM. M. POWELL.
